UNITED STATES PATENT OFFICE.

CHARLES E. WRIGHT, OF WATERBURY, CONNECTICUT.

BAND-SAW GUIDE.

SPECIFICATION forming part of Letters Patent No. 434,010, dated August 12, 1890.

Application filed December 26, 1888. Serial No. 294,582. (No model.)

To all whom it may concern:

Be it known that I, CHARLES E. WRIGHT, a citizen of the United States, residing at Waterbury, in the county of New Haven and

5 State of Connecticut, have invented certain new and useful Improvements in Band-Saw Guides; and I do hereby declare the following to be a full, clear, and exact description of the invention, such as will enable others 10 skilled in the art to which it appertains to make and use the same.

My invention has for its object to produce a guide for band-saws which shall be simple, durable, and economical in construction, 15 which shall hold the saw firmly in any desired position, and in which actual friction or pressure of the parts upon either the sides or back of the saw shall be wholly dispensed with.

20 The important features of my invention are that the back of the saw rests against the side of a disk which is loosely journaled so as to be carried by the saw, and that the sides of the saw rest between adjustable steel 25 guide-plates.

In order that others may understand and use my invention, I will describe the same, referring by numbers to the accompanying drawings, forming part of this specification, 30 in which—

Figure 1 is a side elevation of my novel guide complete; Fig. 2, a front elevation corresponding therewith; Fig. 3, a horizontal section looking down; Fig. 4, a rear view corresponding with Fig. 1, and Fig. 5 a side elevation corresponding with Fig. 1; Fig. 6, a front elevation corresponding with Fig. 2; Fig. 7, an inverted plan view; Fig. 8, a rear elevation, as in Fig. 5; and Fig. 9, a rear elevation of a form of my novel guide in which I have introduced slight changes in the details of construction, which I preferably adopt in guides for heavy saws, it being understood, of course, that the principles of my invention 45 are equally adapted to all classes of bandsaws from the heaviest to the lightest.

1 denotes the body of the guide, which is provided with an arm 2, by which the device is held in place. This arm passes through the 50 horizontal portion of a T-sleeve 3, where it is locked at any desired position by a set-screw 4. In practice the vertical portion of the T-

sleeve is cast solid, and is bored out to fit the special vertical arm (not shown) with which it is to be used, it being secured thereto by a 55 set-screw 5.

The first important feature of my invention consists of a disk 6, rigidly attached to a spindle 7 and carried by the movement of the saw, said spindle turning freely in a 60 socket 8, which slides in the body, being locked at any desired adjustment by a set-screw 9. This disk may be made of vitreous material—for example, glass—or of metal, if preferred.

65 In practice I ordinarily make the disks of hardened steel. The exact diameter of these disks is not of the essence of my invention. They may be made large or small, as preferred, depending to a certain extent upon the class of 70 saws upon which they are used and the work to be performed thereby.

In practice I preferably make the parts of about the proportions shown in the drawings, the disk being for ordinary-sized saws three 75 inches (more or less) in diameter.

Heretofore in this class of guides the backs of the saws have rested against solid supports, against the peripheries of disks, or else against the faces of disks at or near the 80 centers, special mechanism being provided to rotate the disks. None of these systems have proved satisfactory in use. Where a solid back is used, the friction quickly causes sufficient heat to ruin the saw, destroying the 85 temper, causing it to check and frequently to break. If oil is used, it quickly destroys the rubber faces of the large wheels by which the saws are carried. If the back of the saw is placed against the periphery of a disk, the 90 bearing is too short, and the saws bend and frequently break if subjected to any strain. When the saw passes over the face of a disk, if the latter does not rotate, a groove is quickly worn. If the disk is caused to rotate, 95 a complicated mechanism is required, and no advantage is gained, as the scraping of the disk on the saw-back heats and quickly ruins it. If oil is used to overcome that trouble, the large wheels are ruined. In my improved 100 guide the back of the saw rests against the face or side of the disk near the edge thereof, as is clearly shown in Figs. 2 and 6, thereby giving to the saw a firm, straight bearing,

which may be given any reasonable length, depending upon the size of the disk. I thus secure ample bearing-surface for the saw, said surface moving with the saw, and at the 5 same time I avoid friction, avoid complicated mechanism, and avoid the use of oil in connection with the saw itself.

The second important feature of my invention consists of the adjustable tilting guide-10 plates between which the saw rests.

10 denotes the inner guide-plates, which are secured firmly to the body in any suitable manner, ordinarily by screws. 11 denotes the outer guide-plates, which are held in position by central and outer screws 12 and 13, respectively. The outer plate is adjusted to the gage of the saw by means of the central screw 12, which passes through plate 11, and is locked in position by means of the outer 20 screws 13, which pass through the outer guide-plates and bear against the surface of the inner guide-plates. Slight sockets may be provided to receive the points of these screws.

It will of course be understood that it is 25 frequently desirable that the guide-plates between which the saw runs should be farthest apart at their outer edges on account of the thinness of the blade toward the back, or for various other reasons. This I readily 30 accomplish and tilt the outer plate to any desired angle by turning the outer screws 13 in or out, as may be required, ordinarily by turning one in and the other out.

Should it be required to turn the entire 35 guide upon the arm (not shown) by which it is supported, that is accomplished by loosening set-screw 5 and turning the T-sleeve more or less. It will be seen that by these adjustments I am enabled to furnish a guide 40 and support for the entire side of the saw or for any portion of it, as may be required, and without perceptible pressure or friction upon the saw. In changing from wide saws to narrow, or vice versa, the disk is adjusted in or 45 out by loosening set-screw 9 and moving socket 8 and the disk in or out, as may be required.

In the form illustrated in Figs. 5 to 9, inclusive, instead of adjusting the disk in or 50 out for different widths of saws I adjust the guide-plates in or out. This I accomplish by securing the guide-plates to blocks 14, which slide upon guides 15 upon the body, said blocks, and with them the guides, being locked

in position by bolts and nuts 16, which pass 55 through both sliding blocks and the body. In this form I provide an additional adjustment, which enables me to move the entire body and parts carried thereby laterally relatively to the saw. In this form arm 2, instead of being connected to the body, is connected to a slide 17 in the end of the body, which is locked in position by a bolt 18, which passes through a slot in the slide and engages the 60 body.

I wish it distinctly understood that I do not limit my invention to the details of construction illustrated and described, as it is obvious that they may be greatly varied without departing from the principles of my invention.

I claim—

1. A saw-guide consisting, essentially, of a body, a disk mounted therein at one side of the track of the saw, so that said saw will 75 bear against the face of the disk near the edge thereof, and guide-plates between which the saw passes, the disk giving a firm support to the saw and the latter acting to rotate the disk.

2. In a saw-guide, a disk capable of rotation and mounted at one side of the track of the saw which bears against the face of the disk near the edge thereof, so that the forward movement of the saw imparts rotation 85 to the disk, as and for the purpose set forth.

3. In a saw-guide, the combination, with a disk mounted at one side of the track of the saw, so that the saw will rest against the face of the disk near its edge, of tilting guide-90 plates on opposite sides of the saw and screws whereby said plates may be adjusted farthest apart at their outer edges.

4. The combination, with a body and a disk mounted therein at one side of the track of the saw, so that the latter will bear against the face of the disk near its edge, of guide-plates 95 10 and 11 on opposite sides of the saw-track and screws 12 and 13, whereby said guide-plates may be adjusted to saws thinnest 100 at the back.

In testimony whereof I affix my signature in presence of two witnesses.

CHARLES E. WRIGHT.
